UNITED STATES PATENT OFFICE.

JULIUS R. BERNDT, OF CALDWELL, TEXAS.

FILE.

Application filed November 25, 1924. Serial No. 752,198.

To all whom it may concern:

Be it known that I, JULIUS R. BERNDT, a citizen of the United States, residing at Caldwell, in the county of Burleson and State of Texas, have invented certain new and useful Improvements in a File, of which the following is a specification.

This invention relates to improvements in files and has for its principal object to provide a simple and efficient means whereby various records may be kept and filed in an alphabetic order, the files being of such construction as to facilitate access thereto.

One of the important objects of the present invention is to provide a file which includes a cabinet, and a plurality of files arranged therein, means being associated with the cabinet and the files for preventing the displacement of the files from the cabinet.

20 A further object is to provide a means whereby the files may be readily arranged so as to accommodate either small or large records, the cabinet being of such construction as to enable the same to be readily placed in any desirable place without occupying much space.

25 A further object is to provide a file of the above mentioned character, which is simple in construction, inexpensive, strong and durable and furthermore adapted for the purposes for which it is designed.

30 Other objects and advantages of this invention will become apparent during the course of the following description.

35 In the accompanying drawing forming a part of this specification and in which like numerals designate like parts throughout the same:

Figure 1 is a top plan view of the cabinet 40 with the cover removed showing the manner in which the files are arranged within the same.

45 Figure 2 is a longitudinal sectional view taken approximately on line 2—2 of Figure 1 and showing the cover for the cabinet in position thereon.

Figure 3 is a sectional view taken approximately on line 3—3 of Figure 3.

50 Figure 4 is a sectional view taken on line 4—4 of Figure 1.

Figure 5 is a detail perspective view of one of the files and the fastening wire associated therewith, and

55 Figure 6 is a detail perspective view of one of the index cards.

In the drawing, wherein for the purpose

of illustration is shown the preferred embodiment of my invention, the numeral 1 designates generally the cabinet forming a part of the present filing system, the same 60 being substantially rectangular in design and including the side walls 2 and 3 and the front and rear walls 4 and 5 respectively. Side plates 6 and 7 are removably secured to the sides 2 and 3 of the cabinet and the 65 upper edges of the side plates terminate a short distance below the upper edges of the sides as clearly illustrated in Figure 3. Removable end plates 8 and 9 are associated with the front and rear ends respectively of 70 the cabinet and the upper edges of the end plates are substantially flush with the upper edges of the side plates whereby the cover 10 may rest on the upper edges of the removable plates in the manner as also clearly 75 shown in Figure 3.

The front and rear ends 4 and 5 of the cabinet are supported on the cross strips 11 and 12 respectively which extend transversely across the bottom 13 of the cabinet. 80 The front and rear ends of the cabinet are each provided with the aligning vertically arranged spaced slots 14, two of such slots being provided as clearly shown in Figure 1 and the purpose thereof will also herein- 85 after be more fully described.

Partitions 15 extend longitudinally within the cabinet and the ends thereof are slidably received in the aligning slots 14 provided in the front and rear ends of the cabinet. 90 The outer ends of the partitions 15 lie substantially flush with the outer face of the front and rear ends of the cabinet and are normally held against longitudinal sliding movement by means of the end plates 8 95 and 9. The bottom edges of the partitions are spaced from the bottom 13 of the cabinet by means of the strip 16 and similar strips 17 are placed between the bottom edges of the sides 2 and 3 and the bottom 100 13 of the cabinet as clearly illustrated in Figure 3 whereby the upper edges of the partitions all lie in the same plane.

Adapted to be supported within the cabinet 1 are a plurality of files. Each file 18 105 is formed of a single piece of material preferably cardboard which is folded along its longitudinal center as illustrated at 19, the side edges of each file are cut away as illustrated at 20 so that the lower portion of 110 each file will fit between the sides of the cabinet and the shoulders 21 formed by the cut

away portions 20 will cooperate with the upper edges of the sides of the cabinet in a manner as more clearly illustrated in Figure 3. Each file is further slit upwardly from its folded portion 19 as illustrated at 22 for cooperation with the partition 15 whereby the files may be properly placed in the cabinet. The partitions 15 and the slits 22 cooperate whereby each file is preferably divided into three individual compartments of a suitable width. This enables record sheets of a relatively smaller size than the compartments formed by the partitions to be placed in the respective files, the record sheets being preferably filed away in alphabetic order.

An index card such as is shown at 23 is of such width as to enable the same to be inserted in one of the compartments of certain of the files, preferably the central compartment and a tab 24 is formed on the upper edge of the index card and has printed thereon the letter indicative of the first letter of the name on the record sheet or card which is to be filed. The tab 24 of each of the index cards is visible by providing the upper edges of each of the files 18 at the central portion thereof with the cut away portions 25. The purpose of providing a card index of this character is to enable the card to be readily inserted and removed with respect to a file so that any number of files may be used in connection with the filing of records of persons whose names begin with the same letter.

The files are adapted to be supported in the cabinet against accidental displacement therefrom by means of suitable wires shown at 26. The wires extend transversely across the bottom of the cabinet through the strips 16 and 17 and the side plates 6 and 7, which are removably secured to the sides 2 and 3 of the cabinet, cover the ends of the wires so as to prevent the displacement of the same from the cabinet. Each wire 26 engages the folded portion 19 of the respective files in the manner as clearly illustrated in the drawings. This will prevent the files from being moved vertically within the cabinet and in order to remove or insert additional files, it is necessary to remove the side plates 6 and 7 and withdraw the wires to either of the sides of the cabinet.

When it is desired to file records which are of such size as will not permit the same to be received in the compartments formed by the partitions and slots above mentioned, the front end plate 8 is removed from the front end 4 of the cabinet and the partitions 15 are moved longitudinally through the slots 14 in the front end of the cabinet so that the partitions will be entirely removed from the slits 22 provided in the files 18 and the records of a width less than the

width of the cabinet may be inserted in the files.

As is shown in Figure 2 of the drawings, the files are arranged within the cabinet so that ready access thereto may be had and the various letters on the tabs 24 of the index cards 23 are at all times visible so that considerable time will be saved in locating the proper file.

It will thus be seen from the foregoing description, that a filing system has been provided which will save considerable time and labor in retaining records and furthermore the cabinet is of such construction as to enable the same to be readily handled and placed in a suitable receptacle where the same will not occupy any considerable amount of space.

While I have shown the preferred embodiment of my invention, it is to be understood that various changes in the size, shape and arrangement of parts may be resorted to without departing from the spirit of the invention and the scope of the appended claims.

Having thus described the invention, what I claim is:—

1. In a filing system, a cabinet, a plurality of files, means for dividing each of said files into independent compartments, said means comprising spaced partitions arranged in the cabinet, each of said files having slots formed therein for cooperation with the partitions, and means associated with the cabinet for facilitating the removal of the partitions with respect to the cabinet and the files.

2. In a filing system, a cabinet, a plurality of files, means for dividing said files into independent compartments, said means comprising spaced partitions slidable longitudinally through the ends of the cabinet, the ends of the partitions being normally disposed in the slots provided therefor in the respective ends of the cabinet, each of said files having slots formed therein for cooperation with the partitions, and means associated with the ends of the cabinet for facilitating the removal of the partitions.

3. In a filing system, a cabinet, a plurality of files, means for dividing said files into independent compartments, said means comprising spaced partitions, slidable longitudinally through the ends of the cabinet, the ends of the partitions being normally disposed in the slots provided therefor in the respective ends of the cabinet, each of said files having slots formed therein for cooperation with the partitions, and means associated with the ends of the cabinet for facilitating the removal of the partitions, the said last mentioned means comprising removable plates secured on the outer faces of the respective ends of the cabinet.

4. In a filing system, a cabinet, a plural-

- ty of spaced longitudinally extending strips arranged in the bottom of the cabinet, the ends of these cabinets being provided with aligning vertically disposed slots, a plurality of partitions through the aligning slots in the respective ends of the cabinet, the bottom edges of the partitions adapted to rest on the aforementioned strips, the ends of the partitions being disposed in the aligning slots of the ends of the cabinet, each of said files having slots formed therein for cooperation with the partitions, plates movably secured on the outer faces of the ends of the cabinet for normally preventing the accidental displacement of the partitions from the cabinet, and further facilitating the removal of the partitions.
5. In a filing system, a cabinet, a plurality of spaced longitudinally extending strips arranged in the bottom of the cabinet, the
- 5 ends of these cabinets being provided with aligning vertically disposed slots, a plurality of partitions through the aligning slots in the respective ends of the cabinet, the bottom edges of the partitions adapted to 25 rest on the aforementioned strips, the ends of the partitions being disposed in the aligning slots of the ends of the cabinet, each of said files having slots formed therein for cooperation with the partitions, plates mov- 30 ably secured on the outer faces of the ends of the cabinet for normally preventing the accidental displacement of the partitions from the cabinet, and further facilitating the removal of the partitions, and means 35 for securing the files in the cabinets against vertical movement.

In testimony whereof I affix my signature.

JULIUS R. BERNDT.
